UNITED STATES PATENT OFFICE.

MARTIN JELALIAN, OF CRANSTON, RHODE ISLAND.

PROTECTION DEVICE FOR A PERSON AGAINST BULLETS OR EXPLOSIVES.

1,246,274.

Specification of Letters Patent.

Patented Nov. 13, 1917.

Application filed August 30, 1916. Serial No. 117,663.

To all whom it may concern:

Be it known that I, MARTIN JELALIAN, a citizen of the United States, residing at the city of Cranston, in the county of Providence and State of Rhode Island, have invented certain new and useful Improvements in Protection Devices for a Person Against Bullets or Explosives, of which the following is a specification.

- 10 The main object of this invention is to provide a structure of that class adapted to be detachably secured upon the body of a person, and designed to operate in preventing dangerous effects of a bullet or explosive, 15 and its simple but yet most ingeniously arranged construction will be sufficient to serve as a defensive means for the person, when the latter is struck by a bullet or explosive.
- 20 The certain parts of the device are thus arranged that the same will have a limited amount of weight that will be easily carried by the person and at the same time will be a comparatively inexpensive structure to 25 manufacture.

The invention contemplates special features of the construction, combination, and arrangement of parts of the improved device, whereby important utilities are attained and the construction conveniently adapted for use as will be fully set forth.

In the accompanying sheet of drawings, wherein like reference characters indicate like parts, Figure 1, is a side view of my 35 improved device and showing the same as applied to the body of a person. Fig. 2, is a front view of Fig. 1 and showing the parts of the device in their normal position. Fig. 3, is a side perspective view of one of 40 the members of the main section. Fig. 4, is a perspective view of one of the portions of the device which is substantially a semi-cylindrical metallic portion adapted to be secured to the upper leg parts of the person. Fig. 5 is a front view of a modified 45 construction of the main section of the device.

Referring to Figs. 1 and 2, the device comprises two members— 1^2 , 1^2 which form a 50 main section; said members are composed of a metallic bullet-proof structure extending from the top of the shoulders of the person 1, to the lower abdominal part of the same and surrounding the body of the latter.

55 The alike constructed members 1^2 , 1^2 are

provided with hook connections 3 and 3^2 ; securing straps 2, 2 having one of their ends secured to the integral hooks 3 and the other ends attached to the pivotal hooks $—3^2$, 3^2 . The lower part of said metallic 60 structure is also provided with integral hook connections 8^1 , 8^1 , to receive strap connections $—8$, 8 — which are attached as at points $—9^1$, 9^1 . Each of said members carries a pad of suitable yielding material 17 65 upon the inner surface of the same as shown by Fig. 3.

Secured to the head part of the person 1 is a masked device 6^2 composed of a bullet-proof metallic structure which is secured 70 thereto by means of straps $—5$, 5 — said straps are attached as at points 6 and 16^2 as shown in Fig. 1.

The masked device 6^2 is also provided with a pad of yielding material upon the 75 inner surface of the same in the same manner as the alike constructed members or metallic structure $—1^2$, 1^2 .

The members 1^2 , 1^2 of the main section are provided with openings 16, 16— adapted 80 for the arms of the person to pass through the same.

Secured to the upper leg parts of the person 1 are semi-cylindrical bullet-proof metallic structures $—11$, 11 — which are adapted 85 to be secured thereto by means of straps $—11^2$, 11^2 — and also by straps $—8$, 8 —, said structures, $—11$, 11 — are also provided with pads of suitable yielding material 19 upon the inner faces of the same and strap hooks 90 pivotally connected upon their front faces as at $—9^1$, 9^1 .

In Fig. 5 is shown a modified form of the members 1^2 , 1^2 — which consists of one portion 16^3 and is adapted to be secured upon 95 the front part of the person and extending from the top of the shoulders to the lower abdominal part of the person. In this modified construction the latter is provided with securing straps 19^2 , 19^2 — that are connected 100 to the hooks $—17$, 17^1 — along each side of the same, and also strapping means at the upper and lower part thereof, as at points 19^1 and 16^3 , this modified construction also carries a pad of yielding material upon its 105 inner face. It is to be understood that either form may be employed in the construction of the device.

By this construction and arrangement of parts described a device is provided that will 110

positively prevent dangerous effects to a person when the latter is struck by bullets or explosives.

Thus describing my invention what I claim and desire to secure by Letters Patent is:

1. In a device of the character described, a bullet-proof structure, the same consisting of two adjustably connectible alike-constructed metallic sections adapted to be supported by a person and surrounding the body of the latter from the top of the neck to the lower abdominal part thereof, a pair of bullet-proof guards, the same being of a semi-cylindrical shape, detachably secured to the upper leg parts of said person and located at the front part thereof, a pad of yielding material secured upon the inner face of each of said supports, integral and also pivotal strap-hooks carried by said guards and arranged upon each side of the same and having strap connections for attachment to the upper leg parts of the person, a pivotal strap-hook arranged centrally upon each of said leg-supports and strap connections extending from said hooks and connected to

integral hooks carried by said sections and located at the lower parts thereof.

2. In a device of the character described a bullet-proof structure, said structure consisting of a pair of adjustably connectible metallic sections surrounding the body of a person and extending from the top of the shoulders to the lower abdominal part thereof, a mask device, made of a bullet-proof material, detachably secured to the head part of said person and provided with a pad of yielding material upon its inner face and also having integral strap hooks arranged upon each side of the same, strap connections extending from said hooks to the upper end portions of said sections and attached thereto, and said strap connections adapted to keep said masked device in its position upon the head part of the person.

In testimony whereof I affix my signature in presence of two witnesses.

MARTIN JELALIAN.
